UNITED STATES PATENT OFFICE.

DANIEL D. MILLER, OF NEW YORK, N. Y., ASSIGNOR TO WESTERN ELECTRIC COMPANY,
INCORPORATED, OF NEW YORK, N. Y., A CORPORATION OF NEW YORK.

ELECTROMAGNETIC DEVICE.

Application filed May 5, 1921. Serial No. 466,942.

To all whom it may concern:

Be it known that I, DANIEL D. MILLER, a citizen of the United States, residing at New York, in the county of New York, State of New York, have invented certain new and useful Improvements in Electromagnetic Devices, of which the following is a full, clear, concise, and exact description.

This invention relates to electromagnetic relays, and particularly to that type known as polarized relays.

An object of this invention is to provide a simple and extremely sensitive polarized relay of such structure as to successfully avoid residual magnetism in the armature. A second object of this invention is to provide a relay structure that will successfully operate on alternating current to produce sustained operation of an auxiliary circuit.

The relay of this invention is characterized by the use of a polarizing magnet having three prong pole pieces with the middle prong adjustable at both poles and by the magnetic circuits employed wherein the polarizing flux flows across the armature at right-angles thereto and the operating flux flows lengthwise in the armature in opposing directions.

The above mentioned features and other novel features will be more thoroughly understood from the accompanying illustrative drawings and detailed description.

Figure 1 is a perspective view of one embodiment of the relay of this invention showing the three prong pole piece construction with all prongs in the same plane.

Figure 2 is an outline view of the apparatus of Figure 1, showing particularly the electric and magnetic circuits used. A local relay circuit is shown which is useful in conjunction with the alternating current operation of the relay of this invention.

Figure 3 discloses another embodiment of this invention wherein the three prong pole pieces are shown as three prongs or projections on T-shaped bases.

In detail referring to Figures 1 and 2, there is disclosed a permanent magnet 1 having trifurcated pole pieces consisting respectively of members 2 and 4 of fixed lengths relative to the connecting base of the pole piece and member 3 located between members 2 and 4 and adjustable as to its projection; also similar members on the pole pieces of opposite polarity consisting

of members 5 and 7 of fixed length and member 6 located therebetween and adjustable as to its projection. These pole pieces are arranged so that all of the members lie in the same plane with corresponding end faces adjacent. A T-shaped armature is attached between the end faces of the end members of the pole pieces, having one end 8 of the armature head attached between pole piece members 2 and 5 and the opposite end 10 of the armature head attached between end pole piece members 4 and 7. Both ends of this armature head are disclosed as separated from actual contact with the pole piece members mentioned by pieces 38 of non-magnetic material. The shank 9 of the T-shaped armature projects substantially at right angles to the head and at such a position in the armature structure as to bring the junction of the head and shank of the armature adjacent and between the end faces of the middle members of said trifurcated pole pieces. The armature head is slotted at either side of the shank, producing necks or constrictions at the center portion of the armature. The purpose in using an armature of this kind is to allow a more complete motion of its various parts. With this structure, the armature may be considered as fulcrumed either at the junction of the end members of the pole pieces or at the necks joining the shank and head of the T-structure or at both these locations. A more complete discussion of the bending motion in this armature will be given later. A contact member 13 is mounted near the end of the shank 9 of the armature and is cooperable with adjustable contact members 14 and 15 disclosed in this figure as mounted in a supporting metallic frame work, thus short circuiting the contacts 14 and 15. However, this short circuiting feature is involved in but one embodiment of this invention and insulated contacts as illustrated in Figure 3 may be desirable under certain circuit conditions. Energizing windings 16 and 17 are disclosed as surrounding the two ends 8 and 10 of the head of the armature, practically filling the space around said armature head between the end and the middle members of the magnet pole pieces, thus surrounding the major portion of the head of the armature.

Referring more particularly to Figure 2 there is disclosed the same relation of parts

as in Figure 1, but with the electric and magnetic circuits of the relay in question diagrammed in detail. An auxiliary relay circuit is also shown properly connected with the relay of this invention to produce sustained closure of the auxiliary relay contacts upon alternating current energization of the polarized relay. Assuming permanent magnet 1 to be attached to the relay structure so that its N-pole is associated with the upper trifurcated pole-piece and its S-pole with the lower trifurcated pole-piece of the figure, three parallel paths for the flux of the permanent magnet, or the polarizing flux, are formed as disclosed by the light dot-dash lines of the drawings through the pole-piece structure. These paths may be traced from the upper permanent magnet pole of the drawing, in the first case, through left-hand upper pole-piece member 2, left-hand end of armature member 8 and perpendicular thereto, left-hand lower pole-piece member 5 to the lower permanent magnet pole; in the second case, through the adjustable middle member 3 of the upper pole-piece, the upper air gap, the junction end of the shank of the T-shaped armature, the lower air gap, the adjustable middle member 6 of the lower pole-piece, to the lower permanent magnet pole; and in the third case, in a manner similar to the first case mentioned, from the upper magnet pole through the right-hand member 4 of the upper pole-piece, right-hand end of armature member 10 and perpendicular thereto, right-hand lower pole piece member 7 to the lower permanent magnet pole. From the junction of the parallel flux paths in the lower magnet pole, the combined flux traverses the remainder of the polarizing magnetic circuit through the body of the permanent magnet 1. The energizing coils 16 and 17 are disclosed as connected in series and oppositely wound about the two portions of the armature associated with the trifurcated magnet pole-pieces. With like adjustment of pole-piece members 3 and 6 and with no current flowing through the energizing coils 16 and 17, no operating flux will be established and the armature normally, under this condition, will remain in a neutral position. Upon passing a current through the coils 16 and 17 as connected, having the current enter through terminal 39 and leave through terminal 40, operating flux will be established in direction and paths as indicated by heavy dash lines on the drawings. With flux established as shown by the permanent magnet and by the energizing windings, it is evident that there will be a strengthening of the magnetic field in the lower air gap and a weakening of the magnetic field in the upper air gap of the figure, thus producing a net force tending to move the

armature toward pole-piece member 6. The total movement of the armature, under these conditions will comprise two component movements, first the bending or bowing in the pole-piece plane of the head of the T-shaped structure at the points of attachment to the pole-piece junctions and at the necked portions 11 and 12, and secondly, the bending of the shank of the T about the said necked portions toward the lower pole piece prong 6. The result of the total armature movement described is to secure contact between members 13 and 15. Reversal of the current flow in the windings 16 and 17 secures a reversal of all the effects above described, securing as a result the contact of members 13 and 14. Cutting off the current from the windings 16 and 17 secures the complete disappearance of operating flux from the armature due to the opposition of like amounts of flux in the two parts in alignment and therefore the mutual nullifying effect of such fluxes upon deenergization of the windings.

Obviously, the application of alternating current to the windings 16 and 17 will cause a periodic reversal of operating flux in the armature and vibration of the armature in synchronism with the source of current supply. Assuming a source of alternating current supply connected to the windings 16 and 17, armature member 9 will vibrate synchronously with the current supply, thus alternately connecting member 13 with contact members 14 and 15. In the circuit shown the members 14 and 15 are shunted and the shunt connection is in series with a source of electrical energy 18, the energizing winding 19 of the local circuit relay, armature member 9 and contact member 13. With members 14 and 15 properly adjusted, circuit closures will be of relatively long duration and circuit breaks of short duration, resulting in the attraction of the local relay armature 20 and the closing of the circuit it controls at contact point 21 on the first contact make of member 9 and the sustained operation of armature 20 during the period of vibration of member 9 of the polarized relay. This is due to the reestablishment of current and flux in winding 19 before the flux established during a previous contact make of member 9 has had time to die out.

Referring to Figure 3, there is disclosed a permanent magnet 1 having two trifurcated pole pieces. The upper pole piece comprises a T-shaped base 41 having projecting members 22 and 24 of fixed length and perpendicular to the head of the T-shaped base at the ends thereof and member 23 mounted perpendicular to and near the end of the shank of the T-shaped base and adjustable as to perpendicular projection. The lower pole piece disclosed comprises a T-

shaped base 42 having projecting members 25 and 27, of fixed length and perpendicular to the head of the T-shaped base 42 at the ends thereof and member 26 mounted perpendicular to and near the end of the shank of the T-shaped base and adjustable as to perpendicular projection. The pole pieces are so arranged as to bring members 22, 23 and 24 respectively end adjacent to members 25, 26 and 27. A Y-shaped armature, has the ends of its two parallel members 28 and 30 respectively attached to pole piece members 24, 27 and 22, 25 but separated from intimate contact therewith by portions of non-magnetic material 38. The members of the armature are so dimensioned as to bring the junction of members 28, 29 and 30 intermediate the end faces of adjustable pole piece members 23 and 26. A chatterless contact member 31 is attached to the tail 29 of the Y-shaped armature and is positioned so as to be cooperable with adjustable contact members 32 and 33 mounted respectively in supports 34 and 35. Energizing windings 36 and 37 are arranged to surround respectively members 28 and 30 of the armature but with sufficient free core space to permit proper movement of the armature. The electric and magnetic circuits contemplated in the apparatus of Figure 3 are similar in all respects to those described under Figure 2. However, the structural arrangement disclosed in Figure 3 is thought to be more compact and admits of large effective winding space.

What is claimed is:

1. In combination, a permanent magnet, adjustable trifurcated pole pieces for said magnet, an armature cooperable with said pole pieces and energizing coils for said armature.

2. In combination, a polarizing magnet, trifurcated pole pieces for said magnet, each of said pole pieces having one adjust-

able member, an armature fulcrumed at two members of said pole pieces but movable with respect to the third member of said pole pieces, and energizing coils placed in operative relation to said armature.

3. In combination, a polarizing magnet, trifurcated pole pieces for said magnet, said pole pieces having the end faces of corresponding members adjacent, each of said pole pieces having one member longitudinally adjustable, an armature fulcrumed between adjacent members of said pole pieces and movable with respect to said adjustable pole piece members, and energizing coils surrounding the portions of said armature between said pole piece members.

4. A polarized relay structure comprising a polarizing magnet, trifurcated pole pieces therefor, each pole piece having two members of fixed length in the same plane and a third member of adjustable length, a bifurcated armature having the ends of its two arms clamped between adjacent end faces of pole piece members and the junction of said arms movable between the end faces of said adjustable pole piece members, and energizing windings surrounding portions of said armature.

5. A polarized relay structure comprising a polarizing magnet, trifurcated pole pieces therefor, said pole pieces each having two members of fixed length and one member of adjustable length, a bifurcated armature cooperable with said pole piece, members and energizing windings surrounding portions of the armature, said windings being so connected as to produce magnetic flux in said portions either toward or away from the junction dependent on the direction of current flow in said windings.

In witness whereof, I hereunto subscribe as my name this 3rd day of May A. D. 1921.

DANIEL D. MILLER.
